UNITED STATES PATENT OFFICE.

WILLIAM S. GRAHAM, OF CANTON, ILLINOIS, ASSIGNOR TO PARLIN AND ORENDOFF COMPANY, OF CANTON, ILLINOIS, A CORPORATION OF ILLINOIS.

RIDING-CULTIVATOR.

1,092,481.

Specification of Letters Patent.

Patented Apr. 7, 1914.

Application filed May 28, 1913. Serial No. 770,340.

To all whom it may concern:

Be it known that I, WILLIAM S. GRAHAM, a citizen of the United States, residing at Canton, in the county of Fulton, in the State of Illinois, have invented certain new and useful Improvements in Riding-Cultivators, of which the following is a specification, reference being had to the accompanying drawings.

10 This invention relates to riding cultivators and it has for one of its objects the provision of new and improved means for angling the wheels relative to the line of draft and at the same time shifting the shovel-gangs laterally.

Another object of the invention is the improvement of devices of this type in sundry details hereinafter pointed out.

The means by which I have accomplished these objects are illustrated in the drawings and are hereinafter specifically described.

That which I believe to be new is set forth in the claims.

In the drawings, Figure 1 is a top or plan view of my improved cultivator; Fig. 2 is a side view of the machine showing one of the shovel-gangs, with one of the supporting wheels removed for clearness of illustration; Fig. 3 is a top or plan view of my improved cultivator with the shovel-gangs and the parts connected therewith removed, showing the manner of angling the wheels and shifting the shovel-arch laterally; Fig. 4 is an enlarged detail, being substantially a section 35 on line 4—4 of Fig. 1; Fig. 5 is substantially a section on line 5—5 of Fig. 1; and Fig. 6 is a front view of the bracket carried by the seat supporting bars and the anti-friction roller mounted thereon.

40 Referring to the several figures of the drawings in which corresponding parts are indicated by the same reference characters,— 10—11 indicate axle members each comprising a horizontal portion upon which 45 is journaled a supporting wheel 12, a vertical portion and an upper horizontal portion, said axle members being formed either separately or integrally with each other, the upper horizontal portions of said axle members 10—11 being journaled in brackets 13 which are suitably connected to frame-bars 14 at the rear ends of said bars. The forward ends of said bars are connected to a cross-bar 15 upon which a tongue 16 is journaled by means of a bolt 17.

18 indicates a transverse frame-bar extending between the brackets 13.

19 indicates a transverse frame-bar secured to the frame-bars 14 by means of suitable brackets 20.

21 indicates a shovel-arch swingingly held in position by means of substantially vertical bars 22 and diagonal rearwardly-extending bars 23, the bars 22 being connected at their upper ends to the cross-bar 19 and the bars 23 being connected at their upper ends to the brackets 13.

24—25 indicate shovel-beams pivotally supported at their forward ends by means of brackets 26 upon the laterally-extending horizontal ends of the shovel-arch 21. 27 indicates plows mounted in any suitable manner upon said beams 24—25. 28 indicates foot-rests mounted upon said beams.

29 indicates a rock-shaft revolvably mounted upon the frame-bars 14.

30—31 indicate racks fixedly secured upon the rock-shaft 29, one at each side of the machine.

32—33 indicate levers mounted by means of brackets 34 to swing relative to the racks 30—31 respectively, each of said levers being provided with a suitable hand-latch and spring-seated detent for holding the lever in adjusted position relative to the rack as will be readily understood. Each of said brackets 34 is provided with an arm 35 to which is pivotally connected a link 36. Said links 36 are connected at their lower ends by means of chains 37 and links 38 to the shovel-beams 9 24—25, respectively, the effective length of said chains 37 being adjustable as will be readily understood by reason of its hooked connection with the link 36.

39—40 indicate springs connected at their rear ends to the brackets 34 and at their front ends to hooks 41 which pass through suitable openings in arms 42, the forward ends of said hooks being provided with screw-threads upon which thumb-nuts 43 are 14 adjustably secured. Said springs 39—40 tend to draw the brackets 34 forward in clockwise direction as seen in Fig. 2.

44 indicates a rack mounted upon one of the frame-bars 14.

45 indicates a lever fixedly mounted upon one end of the rock-shaft 29 provided with a suitable hand-latch and detent co-operating with the rack 44 for holding the lever in adjusted position relative to said rack, the 1

lever 45 being secured upon the rock-shaft 29 by means of a bracket 46.

47-48 indicate arms fixedly mounted upon the ends of the rock-shaft 29, the lower ends of said arms being connected by means of adjustable links 49 to the vertical portions of the axle members 10-11, respectively.

As will be readily understood, when either lever 32-33 is swung forward relative to its rack 30-31, the corresponding shovel-beam 25-24 is raised through the medium of the links 36-38 and the chain 37, the spring 40 serving to assist in such raising operation. It will also be understood that when both shovel-gangs are in lowered position the lever 45 may be swung forward relative to its rack 44 turning the rock-shaft 29 and with it the brackets 34 and levers 32-33, raising the shovel-beams 24-25 in unison. By such a stroke of the lever 45 the arms 47-48 are also swung backward in clockwise direction in Fig. 2, swinging the axle members 10-11 rearward and shifting the wheels backward relative to the frame as is well understood in the art.

Coming now to the means for shifting the shovel-gangs laterally and for angling the wheels, 50-51 indicate bars secured on opposite sides of the tongue 16 at its rear end. 52 indicates a split collar fixedly mounted upon the upper end of the arch 21, as best shown in Fig. 4, said collar being provided at one side with a boss 53 which is journaled in a suitable opening in the rear end of the bar 51, being held in position therein by means of a suitable bolt 54 passing through said boss. It will be understood that by the means just described the shovel-arch 21 is pivotally mounted relative to the tongue 16. 55-56 indicate brackets secured upon the under side of the cross-bar 19 by means of bolts 57. As best shown in Fig. 5 the brackets 55-56 are in the form of tapered bosses, said bosses having mounted upon them bell-crank levers 58-59, respectively, which are held in position upon the bosses by suitable washers mounted upon the bolts 57. The forwardly-extending arms of said bell-crank levers have pivotally connected to them links 60-61, respectively, the inner ends of which links are pivotally mounted upon a pin 62 passing through suitable openings in the bars 50-51 as best shown in Fig. 4.

55 63-64 indicate seat-frame bars pivotally connected at their front ends to the outwardly-extending arms of the bell-crank levers 58-59, respectively.

65 indicates a bracket suitably connected to said seat-frame bars 63-64 near their rear ends having revolvably mounted upon it a roller 66 which is adapted to rest upon the transverse frame-bar 18 of the machine.

67-68 indicate brackets secured upon the rear of the seat-frame bars 63-64, respec-

tively, by means of a bolt 69 extending from one to the other of said bars.

70-71 indicate seat bars pivotally mounted at their forward ends upon the bolt 69 and provided at their rear ends with a seat 72. As best shown in Fig. 2 the brackets 67-68 are provided at their rear ends with arc-shaped slots 73 concentric about the bolt 69 whereby the seat-bars 70-71 are secured by means of bolts 73 in any desired adjusted position up and down relative to the seat-frame bars 63-64.

As can be understood from an inspection of Fig. 3, when it is desired to shift the shovel-gangs to one side and to angle the wheels so as to carry the machine as a whole sidewise in the same direction, this can be accomplished through the medium of the seat-bar. The act of swinging the seat-bar to the operator's right, as illustrated in said figure, serves to swing both of the bell-crank levers 58-59 in counterclockwise direction in Fig. 3, swinging the rear end of the tongue to the operator's left and moving the shovel-arch 21 in the same direction. Upon this movement of the arch 21 the link 23 on the right-hand side of the machine serves to bring the right-hand end of said shovel-arch closer to the axle member 11, and the link 23 on the left-hand side of the machine serves to force the left-hand end of said shovel-arch farther from the axle member 10. That is to say, not only is the shovel-arch 21 shifted to the left, but also the left-hand wheel is thrown slightly to the rear relative to the shovel arch and much more to the rear relative to the line of draft, serving to move the machine as a whole to the left. As the seat-bar swings toward one side or the other of the machine the roller 66 rolls freely upon the upper face of the frame-bar 18 as will be readily understood. It is designed that the seat-frame bars 63-64 be formed so that their front ends stand normally closer together than the distance between the rear ends of the bell-crank levers 58-59. Consequently when the seat-frame bars 63-64 are connected to said bell-crank levers it is necessary to spring the forward ends of said bars apart against the resiliency of the bars. The bars 63-64 thus serve not only to support the seat and to shift the shovel-arch laterally, but also act to take up all lost motion in the connections of said bell-crank levers and of the links 60-61 with the tongue.

By reason of the construction illustrated, space is left at the center of the machine affording the operator ample opportunity to see the stalks of corn, and also making possible the use of a spreader arch of any well-known type if desired.

What I claim as my invention and desire to secure by Letters Patent is—

1. In a cultivator, the combination of a frame, carrying-wheels mounted thereon, a

- tongue pivotally mounted relative thereto, a lever adapted to swing laterally relative thereto, and connection between said lever and said tongue comprising laterally-extending arms one at each side of said lever whereby the lateral swinging of said lever pushing forward the arm at one side thereof serves to swing the rear end of the tongue toward the opposite side of the frame.
2. In a cultivator, the combination of a frame, carrying-wheels mounted thereon, a tongue pivotally mounted relative thereto, a lever adapted to swing laterally relative thereto, and connections between said lever and said tongue comprising laterally-extending arms one at each side of said lever whereby the lateral swinging of said lever pulling backward the arm at one side thereof serves to swing the rear end of the tongue toward that side of the frame.
3. In a cultivator, the combination of a frame, carrying-wheels mounted thereon, a tongue pivotally mounted relative thereto, a lever adapted to swing laterally relative thereto, and connections between said lever and said tongue comprising laterally-extending arms one at each side of said lever whereby the lateral swinging of said lever serves to push forward the arm at one side and to pull backward the arm at the opposite side swinging the rear end of the tongue relative to the frame.
4. In a cultivator, the combination of a frame, carrying-wheels mounted thereon, a tongue pivotally mounted relative thereto, a lever adapted to swing laterally relative thereto, and connections between said lever and said tongue, said connections comprising a member pivotally mounted on said frame at one side of the line of the tongue adapted to be rocked by the lateral swinging of said lever, by the rocking of which member in either direction the rear end of said tongue is moved laterally in the corresponding direction.
5. In a cultivator, the combination of a frame, carrying-wheels mounted thereon, a tongue pivotally mounted relative thereto, a lever adapted to swing laterally relative thereto, and connections between said lever and said tongue, said connections comprising pivotally-mounted members one at each side adapted to be rocked by the lateral swinging of said lever, by the rocking of which members in either direction the rear end of said tongue is moved laterally in the corresponding direction.
6. In a cultivator, the combination of a frame, carrying-wheels mounted thereon, a tongue pivotally mounted relative thereto, a seat-frame adapted to swing laterally relative thereto, and connections between said seat-frame and said tongue, said connections comprising a member pivotally mounted on said first-mentioned frame at one side of the line of the tongue adapted to be rocked by the lateral swinging of said seat-frame, by the rocking of which member in either direction the rear end of said tongue is moved laterally in the corresponding direction.
7. In a cultivator, the combination of a frame, carrying-wheels mounted thereon, a tongue pivotally mounted relative thereto, a seat-frame adapted to swing laterally relative thereto, an anti-friction roller mounted on said seat-frame adapted to roll on a transverse bar of said frame, and connections between said seat-frame and said tongue, said connections comprising a member pivotally mounted on said first-mentioned frame at one side of the line of the tongue adapted to be rocked by the lateral swinging of said seat-frame, by the rocking of which member in either direction the rear end of said tongue is moved laterally in the corresponding direction.
8. In a cultivator, the combination of a frame, carrying-wheels mounted thereon, a tongue pivotally mounted relative thereto, a lever adapted to swing laterally relative thereto, a shovel-arch pivotally connected with said tongue and adapted to swing laterally relative to said frame, and connections between said lever and said tongue, said connections comprising members pivotally mounted on said frame one at each side of said lever, said connections being adapted to be rocked by the lateral swinging of said lever, by the rocking of which pivotally mounted members in either direction the rear end of said tongue and with it said shovel-arch is moved laterally in the corresponding direction.
9. In a cultivator, the combination of a frame, carrying-wheels mounted thereon, a tongue pivotally mounted relative thereto, a lever adapted to swing laterally relative thereto, a shovel-arch pivotally connected with said tongue and adapted to swing laterally relative to said frame, shovel-gangs pivotally mounted on said arch but held against lateral movement relative thereto, and connections between said lever and said tongue, said connections comprising members pivotally mounted on said frame one at each side of said lever, said connections being adapted to be rocked by the lateral swinging of said lever, by the rocking of which pivotally-mounted members in either direction the rear end of said tongue and with it said shovel-arch is moved laterally in the corresponding direction.
10. In a cultivator, the combination of a frame, carrying-wheels mounted thereon, a tongue pivotally mounted relative thereto, a lever adapted to swing laterally relative thereto, a shovel-arch pivotally connected with said tongue and adapted to swing laterally relative to said frame, and connections between said lever and said tongue,

- 5 said connections comprising a pivotally-mounted member adapted to be rocked by the lateral swinging of said lever, by the rocking of which member in either direction the rear end of said tongue and with it 70
 10 said shovel-arch is moved laterally in the corresponding direction, the lateral swinging of said shovel-arch relative to said frame serving to move slightly forward relative to 75
 15 said frame that side of the arch moving in advance in the lateral swinging of the arch.
11. In a cultivator, the combination of a frame, carrying-wheels mounted thereon, a tongue pivotally mounted relative thereto, a lever adapted to swing laterally relative thereto, and connections between said lever 80
 15 and said tongue, said connections comprising two bell-crank levers one at each side adapted to be rocked in the same direction by the lateral swinging of said first-mentioned lever, by the rocking of which bell-crank levers in either direction the rear end of said tongue is moved laterally in the corresponding direction. 85
12. In a cultivator, the combination of a frame, carrying-wheels mounted thereon, a tongue pivotally mounted relative thereto, a seat-frame adapted to swing laterally relative thereto, a shovel-arch pivotally connected with said tongue, forwardly-extending swinging links connecting said arch with 90
 20 said frame, said links converging slightly toward their forward ends, and connections between said lever and said tongue, said connections comprising a pivotally-mounted member adapted to be rocked by the lateral swinging of said lever, by the rocking of 95
 25 which member in either direction the rear end of said tongue and with it said shovel-arch is moved laterally in the corresponding direction.
13. In a cultivator, the combination of a frame, carrying-wheels mounted thereon, a tongue pivotally mounted relative thereto, a seat-frame adapted to swing laterally relative thereto, a shovel-arch pivotally connected with said tongue and adapted to 100
 30 swing laterally relative to said frame, and connections between said seat-frame and said tongue, said connections comprising laterally-extending arms one at each side of the seat-frame adapted to be rocked by the lateral swinging of said seat-frame, by the rocking of which arms in either direction the rear end of said tongue and with it said shovel-arch is moved laterally in the corresponding direction. 105
14. In a cultivator, the combination of a frame, carrying-wheels mounted thereon, a tongue pivotally mounted relative thereto, a lever adapted to swing laterally relative thereto, and connections between said lever 110
 35 and said tongue, said connections comprising a pivotally-mounted member adapted to be rocked by the lateral swinging of said lever, and a link connecting said pivotally-mounted member with said tongue in rear 115
 40 of its pivot point upon said frame, by the rocking of which pivotally-mounted member in either direction the rear end of said tongue is moved laterally in the corresponding direction. 120
15. In a cultivator, the combination of a frame, carrying-wheels mounted thereon, a tongue pivotally mounted relative thereto, a seat-frame, bell-crank levers one at each side pivotally mounted on said first-mentioned frame, one arm of each of said bell-crank levers being pivotally connected to said first-mentioned lever at that side, and connections between the other arms of said bell-crank lever and said tongue whereby the lateral swinging of said first-mentioned lever in either direction relative to said frame serves to move the rear end of said tongue laterally relative to said frame. 125
16. In a cultivator, the combination of a frame, carrying-wheels mounted thereon, a tongue pivotally mounted relative thereto, a lever, bell-crank levers one at each side pivotally connected to said first-mentioned lever, and connections between said bell-crank levers and said tongue whereby the laterally swinging of said first-mentioned lever in either direction relative to said frame serves to move the rear end of said tongue laterally relative to said frame. 130

tongue pivotally mounted relative thereto, a seat-frame, bell-crank levers one at each side pivotally mounted on said first-mentioned frame, one arm of each of said bell-crank levers being pivotally connected to said seat-frame at that side, connections between the other arms of said bell-crank levers and said tongue whereby the lateral swinging of said seat-frame in either direction relative to

5

10 said first-mentioned frame serves to move

the rear end of said tongue laterally relative to said first-mentioned frame, and an anti-friction roller mounted on said seat-frame adapted to roll on a transverse bar of said first-mentioned frame.
